UNITED STATES PATENT OFFICE.

JOHN L. NEEDHAM, OF CHICAGO, ILLINOIS, ASSIGNOR TO THE BOYE NEEDLE COMPANY,
OF CHICAGO, ILLINOIS, A CORPORATION OF ILLINOIS.

JAR-WRENCH.

1,227,183.

Specification of Letters Patent.

Patented May 22, 1917.

Application filed September 8, 1916. Serial No. 119,111.

To all whom it may concern:

Be it known that I, JOHN L. NEEDHAM, a citizen of the United States, residing at Chicago, in the county of Cook and State of Illinois, have invented a new and useful Improvement in Jar-Wrenches, of which the following is a specification.

This invention pertains particularly to wrenches adapted to the purpose of loosening or tightening the tops, or closures, of fruit-jars and like containers; and the primary object is to provide an improved device, of simple and cheap construction, which is well adapted to the purpose of loosening or tightening closures of varying sizes.

The invention is illustrated in its preferred embodiment in the accompanying drawing, in which—

Figure 1 represents a plan view of a jar-wrench constructed in accordance with my invention, the dotted line indicating the top or closure of a jar; Fig. 2, a bottom plan view of the device, showing the levers more widely separated to admit a larger can-top; Fig. 3 a side edge elevational view of the device, viewing the side which is at the upper portion of the figure in Fig 1; and Fig. 4, a sectional view, taken as indicated at line 4 of Fig. 1.

In the preferred construction, the invention comprises a pair of levers, or jaws, A and B, provided, respectively, with handles A' and B'. One of the levers, preferably the lever A, is provided at its pivot end with a laterally extending arm, or pivot-lug, 1, and the other lever is connected therewith by a pivot 2. Also, one of the levers, preferably the lever A, is provided with two gripping-lugs 3 and 4, while the other lever is provided with a single gripping-lug 5.

The levers are preferably stamped from sheet-metal. The metal at the outer lateral edge of the lever A is bent downwardly to form a flange, which is suitably shaped to provide the bearings, or gripping-lugs, 3 and 4, it being understood that the flange is interrupted between the bearings 3 and 4, where the metal remains in the plane of the lever, thus presenting a comparatively wide lateral opening through the flange and between the bearings 3 and 4, in the space indicated by 6. The down-turned flange is curved inwardly and under at the handle-portion of the lever as indicated at 4^a, and

the grip-portion of the handle is provided with transverse ribs 4^b at the outer curved edge of the handle-grip, so as to prevent the fingers from slipping.

The outer edge-portion of the metal forming the lever B is bent downwardly to provide the closure-gripping lug 5, and is curved inwardly and under, as indicated at 5^a, to provide a suitable hand-grip for the handle B'. The curved outer wall of the handle B' is likewise provided with transverse ribs 5^b, to prevent the fingers from slipping. The metal at the outer edge of the main portion of the lever B is not bent downwardly, but remains in the main plane of the lever, as indicated at 7. Thus, the flange which forms the closure-grip 5 is interrupted, or, in effect, cut away from the grip 5 to the pivot-end of the lever.

From the description given, it will be understood that the body-portions of the levers have a plane or substantially flat lower surface adapted to rest upon the top of the can, while the closure-grips 3, 4 and 5 will grip the circumferential portion of the jar-closure.

The metal of the body-portions of the levers is struck upwardly to form external longitudinal strengthening ribs 8.

In the use of the device, the levers are separated sufficiently to embrace the circumferential portion of the closure between the lugs 3, 4 and 5. When the handles are pressed together, the jar-closure is firmly gripped between the closure-gripping lugs and the closure may be readily loosened and removed from the jar. It will be observed that the closure-gripping lug 5 is a considerable distance from the pivot 2, the result being that the lug 5 will grip the closure some distance beyond a diametrical line passing through the center of the closure and a point mid-way between the lugs 3 and 4. This will be true, even of quite a large closure, so that it will be understood that the wrench is universal for a large range of sizes. Three closure-grips employed on levers in this manner are sufficient to effectively grip the closure. By making one of the levers of angular form, or providing a lateral projection which is integral with the lever, and which serves as a pivot-ear, the construction is simplified, and the manipulation of the device is facilitated.

A device of the description given may be durably made and of handsome appearance, and may be manufactured thus at moderate cost.

5 The foregoing detailed description has been given for clearness of understanding only, and no unnecessary limitation should be understood therefrom, but the appended claims should be construed as broadly as 10 permissible, in view of the prior art.

What I claim as new, and desire to secure by Letters Patent, is:

15 1. A jar-wrench comprising a lever having a lateral pivot-ear at one end and a substantially straight lever pivotally connected at one end to said ear, one of said levers being equipped on its under side with a pair of closure-gripping lugs and the other being equipped on its lower side with a single closure-gripping lug.

20 2. A jar-wrench comprising a pair of pivotally-connected sheet-metal levers having the lateral outer edge-portions of the levers curved downwardly to afford closure-gripping lugs and curved at the handle-portions 25 of the levers to afford handle-grips, said

closure-gripping lugs being spaced to admit the closure between them.

3. A jar-wrench comprising a lever having a lateral projection at one end affording a pivot-lug and having the outer lateral edge-portion provided with a down-turned flange which is interrupted to afford closure-gripping lugs, and a companion lever pivotally connected with said pivot-lug and 30 having its outer lateral edge-portion equipped with a closure-gripping lug.

35 4. A jar-wrench comprising a sheet-metal lever having a laterally-projecting pivot-lug at one end and having the outer lateral edge-portion of the metal bent downwardly to afford closure-gripping lugs and a handle-grip, space being left between the closure-gripping lugs to admit the closure, and a companion sheet-metal lever having one end 40 pivotally connected with said pivot-lug and having the outer edge-portion of the metal bent downwardly to afford a pivot-gripping lug and having the metal curved downwardly and under to afford a handle-grip. 45
